(57) **CLAIM**

The ornamental design for a toilet cleaning device, as shown and described.

DESCRIPTION

FIG. 1 is a perspective view of a toilet cleaning device, according to the present design;

FIG. 2 is another perspective view of the toilet cleaning device of FIG. 1;

FIG. 3 is a left side view of the toilet cleaning device of FIG. 1;

FIG. 4 is a front view of the toilet cleaning device of FIG. 1;

FIG. 5 is a right side view of the toilet cleaning device of FIG. 1;

FIG. 6 is a rear view of the toilet cleaning device of FIG. 1;

FIG. 7 is a top view of the toilet cleaning device of FIG. 1; and,

FIG. 8 is a bottom view of the toilet cleaning device of FIG. 1.

The design consists of the feature of shape, configuration, pattern, and ornament of the toilet cleaning device shown in solid lines in the drawings. The portions of the article shown in broken lines form no part of the design.
